UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

TRAVERSING MECHANISM FOR TWIN STEREOTYPE PLATE CASTING MACHINES

Application filed September 10, 1926, Serial No. 134,695. Renewed September 27, 1929.

This invention relates to a stereotype plant or machine in which stereotype plates are cast in two or more boxes or molds and finished in a single finishing machine which moves to take care of the products of all the casting machines.

The principal object of the invention is to provide an automatic traversing device for a finishing machine in which the machine will move from one position to another in a time less than that required to finish the plates, so that it will be in its delivering position before the finishing operation is completed and the operator can be there ready to assist in the discharge of the plate and will not have to be there merely at the time the machine stops moving laterally; also to provide means connected with the shaving shaft for traversing the shaving machine, and means for throwing the traversing means out of gear automatically at the desired times to secure the above mentioned result; and to provide means whereby the machine can be started conveniently from either side by hand and will then stop automatically at the other side with the shaving shaft still running.

Other objects and advantages of the invention will appear hereinafter.

Reference is to be had to the accompanying drawings in which

Fig. 1 is a plan of a casting and finishing plant of the twin type showing a preferred means of applying this invention thereto, the finishing machine itself being indicated only in dotted lines to show one of its positions;

Fig. 2 is a central longitudinal vertical sectional view through the finishing machine showing one of the casting machines in elevation;

Fig. 3 is an end view of the finishing machine;

Fig. 4 is a side view of the end of the finishing machine;

Fig. 5 is a plan of the end of the finishing machine; and

Fig. 6 is a plan of the operating rack shown in a modified form.

As stated, the present invention relates to a plant in which a single finishing machine 10

is mounted to swing or otherwise move so as to take care of the product of two or more casting machines 11. These are shown as receiving metal from a pair of pumps 12 in a melting pot 13, but that is immaterial.

I have not illustrated or described any particular form of casting box as this machine is intended to be used with any ordinary kind, but I have indicated a well known form for convenience.

The two casting machine frames are mounted in fixed position as shown here, with their central lines converging to a point, about which point the finishing machine swings to receive the products from them alternately and finish them.

In accordance with the present invention, the whole machine is run from one motor, but the traversing operation is completed before the finishing operation. The finishing machine, therefore, comes to rest in line with the empty casting box while the shaving shaft and trimmers are still operating. This permits the operator, before the finishing operation has been completed, to go from the point at which he starts the machine to the far end of the machine and be ready to remove the plate.

The finishing machine comprises a frame 10 mounted on a vertical shaft or stud 16 about which it can swing. It has a concentric track 17 on which a pair of rollers 18 on the frame 10 travel, and also a concentric rack 19 adjacent to this track for the purpose of swinging the frame as will appear.

On the frame 10 is a motor 20 which, through gearing, directly operates the planetary trimming saw or saws 22. The saws are rotatable bodily about the shaving shaft 21 of the finishing apparatus. On the end of the shaving shaft is a worm gear 23, which is driven by suitable gearing from a shaft 24. To this shaft is fixed one of the train of gears from the motor to the planetary saw. The shaft 24 has a pinion 25 on the end which drives a spur gear on which is fixed a bevel gear 26. This bevel gear meshes with two opposite bevel gears 27, either one of which can be connected by a sliding clutch 28 with a vertical shaft 29 on which they are freely

mounted. This shaft 29 is mounted in brackets 30 on the finishing machine, and is provided with a pinion 31 at the bottom meshing with the rack 19. It will be obvious that the frame 10 will swing about the center 16 in accordance with the direction of rotation of the shaft 29 as controlled by the clutch.

This clutch is controlled by a clutch lever 33, which can be operated from either side by handles 34. Each handle is on a vertical rock shaft 35. This shaft has arms 36 operating a shifter 37 on a horizontal rod 38 connected with the ends of the two sets of arms 36 at the opposite sides of the machine. The operation of either of these handles 34 will swing the clutch lever 33 on its pivot 39 and throw the clutch one way or the other.

The clutch lever is provided with a toe 40 adapted to engage one of a pair of fixed stops 41 at the ends of its traverse, these stops being located on the track. This constitutes the clutch operating mechanism.

The clutch mechanism is interlocked with a pair of handles 43 on the two sides of the machine but on the same shaft. They have projections 44 adapted to engage projections 45 mounted on the arms 36 or otherwise connected with the clutch operating mechanism. These are arranged so that the clutch cannot be engaged when the handles 43 are in the position shown in Fig. 4. They have to be raised to allow the clutch to be brought out of neutral position.

The starting of the motor is accomplished through a switch 46 which is operated from the bell crank operating lever 33 through a connection 47 thereon. The stopping of the motor at the end of the finishing operation is accomplished by a similar switch 48 operated by a pin 49 on the worm wheel 23 of the shaving shaft.

In Fig. 6, I have shown the rack as consisting of a chain 50 stretched taut on a curved surface 51 and engaged by a sprocket wheel 52 which I regard as the equivalent of the rack and pinion shown in the other figures.

In the operation of the device, assuming the parts to be in the position shown in Fig. 1, with the left-hand box just having delivered its casting to the finishing machine, the two handles 43 are lifted by the operator stationed at the left to avoid interference of the projections 44 and 45. Then the handle 34, which is on the outer side convenient to the operator, is turned to throw the clutch in and close the starting switch 46. This, of course, starts the motor 20 with the clutch in so that the first part of the operation will turn the shaving shaft and the tail cutter, and also at the same time swing the frame 10 about its pivot due to the rolling of the pinion 31 along the rack 19. Now when the shaving device has turned to a position in alignment with the other casting box, the

stop 41 at that time will be engaged by the toe 40 and will automatically turn the clutch to neutral position. The shaft 21 will continue to operate to complete the finishing operation, however. The attendant has time to get over into the proper position to take out the plate or receive it and place it in the cooling saddle 53 or remove it from the machine. Then he goes to the opposite side of the machine to start it again in the same way. It will be understood, of course, that during this period the plates are being cast and cooled in the other box ready to be delivered to the machine before it starts back. After the finishing machine stops in its second position, the levers 43 are turned down so that the machine cannot be started accidentally or by any one merely turning one of the handles 34.

This invention economizes in the first cost of a plant because one finishing machine can take care of the product of two casting boxes on account of the delay necessitated by the cooling of the plates. It provides automatic and efficient means for traversing the finishing mechanism in such a way that it will come to rest as a whole before the finishing or shaving shaft has completed its entire operation, thus furnishing the advantages above mentioned.

Although I have illustrated and described only one form of the invention I am aware of the fact that changes can be made therein by any person skilled in the art without departing from the scope of the invention as expressed in the claims. Therefore, I do not wish to be limited to the exact form shown, but what I do claim is:

1. The combination with a single movable finishing machine and a plurality of casting devices co-operating therewith, of means for moving the finishing machine from a position in alignment with one casting device to a position in alignment with another and stopping it there, and means for continuing the operation of the finishing mechanism afterwards.

2. The combination with two casting devices arranged with their longitudinal axes intersecting, of a finishing machine pivoted to swing about the line of intersection as an axis, means for traversing the finishing mechanism through the arc from one casting device to the other, and means for automatically stopping the traversing mechanism before the finishing operation is completed.

3. The combination with a pair of casting devices located with their longitudinal axes intersecting, of a finishing machine pivoted on the line of intersection of said axes from a position in line with one casting device to a position in alignment with the other, a motor for operating the finishing mechanism on the finishing machine, means operated by said motor for traversing the

finishing machine from one position to the other, and means whereby the traverse of the finishing machine will be completed before the finishing operation is completed.

4. The combination with a casting device and a finishing device movable toward and from it to receive and discharge the products thereof, of a motor carried by the finishing machine, a shaving shaft on the finishing machine connected with the motor to be operated thereby, a traversing device for the finishing machine, a clutch connection for throwing the traversing device in and out of operation and reversing it, and means for throwing 10 the clutch into neutral position before the shaving shaft has completed its entire revolution, so that the finishing machine will be in its final delivering position before the finishing operation is completed.
5. The combination with a pair of casting devices and a finishing device swinging on an axis from one to the other to receive the products thereof alternately, of a motor carried by the finishing machine, a shaving shaft on the finishing machine connected with the motor to be operated thereby, a traversing device for the finishing machine, a clutch connection for throwing the traversing device in and out of operation and reversing it, means for throwing the clutch into neutral position automatically before the shaving shaft has completed its entire revolution, a starting switch for the motor, and 30 means connected with the clutch shifting device for throwing the switch in when the clutch is connected.

6. The combination with a casting device and a movable finishing device, of a motor 40 carried by the finishing machine, a shaving shaft on the finishing machine connected with the motor to be operated thereby, a traversing device for the finishing machine connected with the shaving shaft to be operated thereby and having a clutch connection for throwing it in and out of operation and reversing it, a stationary stop adjacent to the casting device, and a clutch shifting device having an arm in position to engage said stop 50 at the end of the stroke of the finishing machine for throwing the clutch into neutral position before the shaving shaft has completed its entire revolution.

7. The combination with a pair of casting devices and a finishing device movable from one to the other to receive the products thereof alternately, of a motor carried by the finishing machine, a shaving shaft on the finishing machine connected with the motor to be operated thereby, a traversing device for the finishing machine connected with the shaving shaft to be operated thereby and having a clutch connection for throwing it in and out of operation and reversing it, a bell-crank for 60 shifting the clutch, a rod transverse to an arm

of the bell-crank having means for engaging said arm and turning the bell-crank, and two levers, one at each side of the finishing machine connected with said rod for shifting it by hand.

8. The combination with a pair of casting devices and a finishing device movable from one to the other to receive the products thereof alternately, of a motor carried by the finishing machine, a shaving shaft on the finishing machine connected with a motor to be operated thereby, a traversing device for the finishing machine connected with the shaving shaft to be operated thereby and having a clutch connection for throwing it in and out of operation and reversing it, a bell-crank for shifting the clutch, a rod transverse to an arm of the bell-crank having means thereon for engaging said arm and turning the bell-crank, two levers, one at each side of the finishing machine connected with said rod for shifting it by hand, and a pair of stops, each of which is in position to engage the arm when the finishing machine reaches the end of its traverse so that the finishing machine will be in its final delivering position before the finishing operation is completed.

9. The combination with a casting device and a movable finishing device, of a shaving shaft on the finishing machine, a traversing device for the finishing machine connected with the shaving shaft to be operated thereby and having a clutch connection for throwing it in and out of operation, a bell-crank for shifting the clutch, a rod having means for engaging the arm of the bell-crank and turning it, a lever at the side of the finishing machine for shifting said rod by hand, and a pair of arms having lugs thereon for preventing the operation of the shifting means except when they are turned out of the way.

10. The combination with a single movable finishing machine and a plurality of casting devices cooperating therewith, of means for moving the finishing machine while engaged in finishing a plate from a position in alignment with one casting device to a position in alignment with another, and means for continuing the operation of the finishing mechanism afterwards.

11. The combination with two casting devices arranged with their longitudinal axes intersecting, of a finishing machine pivoted to swing about the line of intersection as an axis, means for traversing the finishing mechanism through the arc from one casting device to the other while in the operation of finishing a plate.

In testimony whereof I have hereunto affixed my signature.
